UNITED STATES PATENT OFFICE.

WALTER KENNEDY, OF CLIFFSIDE, NEW JERSEY.

DESIGN FOR A HEATER.

Application filed May 23, 1923. Serial No. 6,250. Term of patent 3½ years.

To all whom it may concern:

Be it known that I, WALTER KENNEDY, a citizen of the United States, residing at Cliffside, county of Bergen, State of New Jersey, have invented a new, original, and ornamental Design for Heaters, of which the following is a specification, reference being had to the accompanying drawings, forming part thereof.

Fig. 1 is a front view of a heater showing my new design. Fig. 2 is a view looking from right to left thereof.

I claim:

The ornamental design for a heater as shown.

Dated, this 22nd day of May, 1923.

WALTER KENNEDY.
